UNITED STATES PATENT OFFICE.

JAMES JOSEPH KEHOE, JR., WILLIAM CHARLES TREW MORSON, AND ERIC MICHAEL DE SHERBININ, OF TORONTO, ONTARIO, CANADA, ASSIGNEES, BY MESNE ASSIGNMENTS, TO PARAGON DISHWASHER SYNDICATE INCORPORATED, A CORPORATION OF NEW YORK.

SPLASHPROOF CABINET FOR DISHWASHING AND SIMILAR PURPOSES.

Application filed November 10, 1923. Serial No. 674,094.

This invention relates to a splash proof cabinet, in which one or more water streams are discharged in all directions, under pressure and so constructed that there can be no leakage from the interior, to the exterior. To this end the top, in its preferred construction, comprises an open frame, surrounding and contacting the outer surfaces of the vertical walls above and below their top edges, and a pan-shaped panel, within the inner surface of the walls, having an outwardly extending rim overlying the top edges of the walls and secured to the frame; the pan and frame forming groove like recesses in which the top edges of the vertical walls are entered. Splash strips of angle metal are secured to the inner surfaces of the vertical walls and cover the joints formed by the vertical walls and cabinet top and vents are formed through the panel for the escape of the vapor from, and for creating a draught through, the cabinet, this draught accelerating the drying of the cabinet contents. The vapor vents are protected by a shield which prevents the water splashing through them and the ends of this shield are open to establish a channel of communication between the interior of the cabinet and the vents. The invention further relates to means, protected from contact with the water streams, for lighting the interior of the cabinet. In the drawings: Fig. 1 is a front elevational view of the cabinet, Fig. 2 is a side elevational view of the same, Fig. 3 is a vertical section on the line 3—3, Fig. 1, Fig. 4 is a vertical sectional elevational view on the line 4—4, Fig. 2. Like characters of reference refer to like parts throughout the specification and drawings. The cabinet comprises two vertical side walls 1, a back 2, front 3, and bottom 4. These may be of any usual or approved design and are preferably constructed of sheet metal. In the front 3 is an opening 5 closed by a sliding door 6 having a transparent section or panel 7 through which the interior of the cabinet can be viewed. Within the cabinet are water pipes 8 having outlets through which water streams are discharged under pressure and within the cabinet, preferably near the top is an electric lamp, for illuminating the interior of the cabinet, having conductors extending through the walls of the cabinet for supplying current and a transparent water-tight globe 10 enclosing it and protecting it from the water streams and vapor within the cabinet. The top of the cabinet comprises an open frame 11 surrounding the walls 1, 2 and 3 and extending above and below the top edges of the walls, and a pan-shaped panel 12 within the walls, the inner surface of which is below the top edge of the frame. The sides of the panel converge, and are of such depth as to form, in combination with the frame, grooves 13 in which the upper ends of the walls 1, 2 and 3 are entered. Extending outwardly from the top of the panel 12 is a rim 14 connected to the frame 11 and overlying the top edges of the walls 1, 2 and 3. Protecting the grooves are splash strips 15 secured to the inner surfaces of the walls immediately below the cabinet top and extending across the grooves 13 a sufficient distance to entirely cover them. These splash strips are made of angle metal and their sides 16 riveted to the inner surfaces of the vertical walls and their sides 17 overlying the grooves, the intervals between the rivets providing sufficient clearance space for drainage between the splash strips and the walls. Formed through the panel 12 are vapor vents 18 and fastened to the inner surface of the panel is a shield 19 covering the vents 18 for preventing the water being splashed through them. The ends of the shield 19 are open to establish a channel between the interior of the cabinet and the vents. When the sliding door is raised atmospheric air from the exterior of the cabinet enters the apparatus and filling the lower part of the cabinet lifts the vapor bodily towards the top and evacuates it through the vents 18. The vapor being evacuated from the interior of the cabinet, this air assisted by the heated condition of the contents effects the instantaneous drying and polishing of the dishes. This polished condition of the dishes could not be effected otherwise.

than by an instantaneous evacuation of the vapor from the interior of the cabinet and this evacuation is only possible by providing vapor vents at or near the top of the apparatus and introducing the exterior air into the cabinet at or near the bottom so that the introduction of the exterior air will lift the vapor bodily and force it through the vents without causing condensation. The water pipes 8 are arranged at different elevations within the cabinet and their nozzles are provided with spinners 20 which scatter the water vertically, radially and tangentially to all parts of the cabinet interior with sufficient force for it to penetrate any through joint. By means of the construction above outlined it is impossible for the water to be forced through the joint formed by the vertical walls and the cabinet top or through the vent openings for the vapor as the overhanging rims arrest the outward penetration of the water at the joints and the shield stops it reaching the vent openings, and the splash strips which are secured to the cabinet walls for protecting the joints prevent it reaching the joints with any degree of force and direct it when this force is expended downwardly to the cabinet bottom by direct fall from the top and by drainage down the inner surfaces of the vertical sides. One or more of the water pipes 8 is or are revolvably adjustable for changing the direction of the stream outlets towards the contents of the cabinet and each of these pipes extends beyond the exterior of the vertical walls and is provided with means, such as a handle or crank 22, by which it can be rotatably adjusted. As the direction of the streams is changed from time to time by the revoluble adjustment of the pipes, it is necessary to provide for the inspection of the interior and for this purpose the cabinet is constructed with a transparent section and provided with the illuminating lamp. This construction and equipment renders the interior of the cabinet visible and allows of the accurate direction of the water streams to the part or parts of the cabinet where they

can most effectively perform their function.

Having thus fully described my invention, what I claim as new and desire to secure by Letters Patent is:

1. In a dishwashing machine a cabinet having vertical side, back and front walls and a bottom, and an opening in the front wall closed by a sliding door, a cabinet top comprising an open frame surrounding the upper ends of the side, back and front walls and extending above and below the top edges thereof, a pan shaped panel connected to the frame, overlying the frame above said walls and extending below their top edges and converging within the cabinet to provide grooves in which the upper ends of the walls are entered, and splash strips secured to the inner surfaces of the walls immediately below the cabinet top for covering the grooves and protecting the joint formed by the top edges of the walls and cabinet top. 50 55 60 65 70

2. In a dishwashing machine a cabinet having vertical side, back and front walls and a bottom, and an opening in the front wall closed by a sliding door, a cabinet top comprising an open frame surrounding the upper ends of the side, back and front walls and extending above and below the top edges thereof, a pan shaped panel connected to the frame, overlying the frame above said walls and extending below their top edges and converging within the cabinet to provide grooves in which the upper ends of the walls are entered, splash strips secured to the inner surfaces of the walls immediately below the cabinet top for covering the grooves and protecting the joint formed by the top edges of the walls and cabinet top, vapor vents formed through the panel and a shield fastened to the inner surface of the panel covering the vents, the ends of the shield being open to establish a channel between 75 80 85 90 95 the interior of the cabinet and the vents.

Dated at the said city of Toronto, this 30th day of May, A. D. 1923.

JAMES JOSEPH KEHOE, Jr.

WILLIAM CHARLES TREW MORSON.

ERIC MICHAEL DE SHERBININ.
